[57] CLAIM

The ornamental design for a protective sheet for house plant husbandry, substantially as shown and described.

DESCRIPTION

FIG. 1 is a top plan view of the left one-half portion of the protective sheet for house plant husbandry, showing our new design;

FIG. 1A is a top plan view of the right one-half thereof; and

FIG. 2 is a side elevational view thereof.

The sheet is of no substantial thickness and the opposite surface to that shown is substantially plain and unornamented.
